UNITED STATES PATENT OFFICE

162,153

COMBINATION PAD AND PENCIL HOLDER

Charles F. Gilfert, Chester, Pa.

Application December 6, 1949, Serial No. 6,437

Term of patent 14 years

(Cl. D74—21)

To all whom it may concern:

Be it known that I, Charles F. Gilfert, a citizen of the United States of America, residing at Chester, in the county of Delaware and State of Pennsylvania, have invented a new, original, and ornamental Design for Combination Pad and Pencil Holder, of which the following is a specification, reference being had to the accompanying drawing, forming a part thereof.

Fig. 1 is a perspective view of a combination pad and pencil holder, showing my new design;

Fig. 2 is a bottom plan view thereof; and,
Fig. 3 is a side elevational view thereof.

I claim:

The ornamental design for a combination pad and pencil holder, as shown.

CHARLES F. GILFERT.
